BALANCE STOP FOR DOOR TYPE ELEVATORS

Herbert E. Grau, Los Angeles, Calif., assignor to
Byron Jackson Co., Huntington Park, Calif.,
a corporation of Delaware

Application March 29, 1937, Serial No. 133,608

8 Claims. (Cl. 294—91)

This invention relates to a balance stop construction for door type slip elevators such as employed in handling tubing or drill strings in operations at the mouth of a deep well. This 5 type of elevator is in the form of a split collar comprising two pipe encircling members one of which is a body member extending across the back, the other part being a door connected to the body at one side by a movable joint or hinge. 10 The door is capable of being swung to an open position to permit the elevator to be applied to the tubing, or to permit the tubing to be removed from the elevator. This type of elevator is used largely with weldless supporting links, which engage 15 the outwardly projecting lugs on the pipe encircling members to support the elevator. The lower end of each link has an eye, which receives the lug, and in order to permit the insertion of the lug through the eye, it is necessary to have considerable play between the side faces of the 20 lug in the adjacent faces of the eye. On account of this play or clearance between the lug and the face of the eye, when the door of an elevator of this type is in its open position, the weight 25 of the door unbalances the elevator and would permit the elevator to tilt forwardly so that the elevator would not be held in its normal or upright position. In order to overcome this objection and maintain the elevator upright in its open position, it has been the practice heretofore to employ an adjustable bolt mounted in the face of the lug near its upper and forward side, and this bolt is adjusted outwardly to engage the adjacent face of the link, thereby taking 30 up the play or clearance referred to. The contact between the head of the bolt and the adjacent face of the eye usually takes place along the edge of the bolt head, and although the bolt may be screwed out further to effect a better contact with the face of the eye, this necessitates a relatively long shank on the bolt and a longer threaded opening in the lug, both of which are objectionable. Furthermore, various sizes of links may be and are used with a 35 given elevator. The size of the eyes in these links vary, and their angular position with respect to the elevator ear varies also. Either or both of these variations results in a poor contact between the link and elevator ear, thus permitting 40 the elevator to tilt when open.

An object of the present invention is to provide a balance stop construction for slip elevators of this type, which can be readily applied so as to take up the clearance between the lug and the eye, and at the same time, provide an effec-

tive contact with the face of the eye, regardless of the size of the eye in the link, or its angular position with respect to the elevator ear.

A further object of the invention is to provide a balance means employed in a lug for this purpose, with a cap which can be applied to the same to take up the clearance; also, to construct these parts in such a way that they will cooperate to take up the clearance between the lug and the eye to support the elevator in an 10 upright position when it is open.

A further object of the invention is to provide cooperating means between the cap and the lug, which will operate to prevent any rotation of the bolt after the cap has been applied to it. 15

Further objects of the invention will appear hereinafter.

The invention consists in the novel parts and combination of parts to be described hereinafter, all of which contribute to produce an efficient 20 balance stop for door type elevators.

A preferred embodiment of the invention is described in the following specification, while the broad scope of the invention is pointed out in the appended claims.

In the drawing:

Fig. 1 is a horizontal section taken through the eyes of the elevator links about on the line 1—1 of Fig. 2, and illustrating the elevator in its open position.

Fig. 2 is a side elevation of the elevator illustrated in Fig. 1, but upon an enlarged scale. This view is a fragmentary view, and represents the end of the lug in elevation with the upper portion of the link and adjacent portions of the 35 elevator broken away.

Fig. 3 is a partial section taken about on the line 3—3 of Fig. 2, but upon an enlarged scale, and illustrating the preferred details of construction for the head of the bolt and cap.

Referring more particularly to the parts, the elevator 1 is composed of two pipe encircling members comprising a body member 2a and a door member 2b, which are connected together at one side preferably by a hinge connection 3, 45 which permits the members 2a and 2b to swing apart as illustrated in Fig. 1, to open the elevator for the admission or removal of the tubing. The outer side of each member 2a, 2b, is provided with an outwardly projecting lug 4. These lugs 50 are supported in the eyes 5 of weldless links 6.

As indicated in Fig. 2, which shows the end elevation of one of the lugs, these lugs taper in an upward direction so as to present side faces, or cheeks 7, which have a curvature or 55

contour approximating that of the adjacent inner faces 8 of the eye 5. The outer end of each lug is provided with a downwardly projecting bill 9 to prevent the eye from slipping off from the 5 lug.

As indicated in Fig. 2, a considerable amount of play or clearance is necessary, forming a gap 10 at the forward side of the lug, and unless some means is provided to eliminate this play or clearance, the elevator will tilt forward when in the 10 open position.

In applying my invention, I provide means mounted in the forward face or cheek 7 of the lug, and this means projects outwardly toward 15 the adjacent face of the eye; and I provide a cap or similar means cooperating with the same to effect an adjustment at this point, and fill the gap between the lug and the face of the eye. In order to accomplish this, I prefer to provide the 20 lug with a threaded opening 13 to receive the threaded shank of a bolt 14, said bolt being preferably provided with a substantially square head 15 (see Fig. 3). This bolt may be adjusted outwardly by means of a wrench applied to its head, 25 or by means of a small lever bar inserted in threaded sockets 16 provided in the side faces of the bolt head, the purpose of which will presently appear.

On the head of the bolt I provide a cap 17, 30 which is preferably in the form of a slightly elongated block having a wide slot 18 cut into the same on its bottom side, and extending in from one end, said slot being sufficiently wide to receive the shank of the bolt 14, and the sides of 35 this slot are cut with channels 19 to receive the bolt head. After the bolt has been adjusted out sufficiently, the cap or block 17 is slid from the outer side over the bolt head 15, and when the cap is applied the bolt 14 should be in a position 40 such that the upper or outer face of the cap will engage the face 8 of the eye. In this way substantially all the clearance existing at this gap 10 will be taken up.

I prefer also, to provide means for retaining 45 the cap on the bolt head, and for this purpose the butt end 20 of the cap is provided with a pin or small threaded bolt 21, which passes in through the end of the cap and has threaded engagement with any one of the threaded sockets 16. If desired, a cotter 22 may be provided 50 alongside of the reduced neck 23 on this small bolt or screw 21, to prevent the same from working out accidentally. If desired, a spring washer 24 may be applied under the head of this threaded pin or screw 21.

Elevators of this type are usually provided with outwardly projecting handles 2c at the front, to facilitate the opening and closing of the elevator.

I prefer to provide means cooperating with the 60 cap to prevent its rotation, and thereby prevent rotation of the bolt 14. For this purpose, at the face 7 where the bolt 14 is applied, I may provide a shoulder 25, which is engaged by the lower side face of the cap or block 17 when it is slid into 65 position.

It will be evident that an elevator having this improvement will maintain itself in an upright position when open; and, furthermore, the device constituting this improvement can be readily 70 adjusted to adapt it to variations in the eyes of different elevator links that may be applied on the lugs.

While I have indicated my improvement as applied on both of the lugs of this elevator because 75 this is preferable, nevertheless, it should be un-

derstood that if the improvement is applied to only one lug, it would still perform the function of supporting the elevator upright when open; but it is obvious that in order to relieve undue strains on a single device, it is preferable to 5 employ two as illustrated.

It is understood that the embodiment of the invention described herein is only one of the many embodiments this invention may take, and I do not wish to be limited in the practice of the 10 invention, nor in the claims, to the particular embodiment set forth.

What I claim is:

1. In a balance stop construction for door type 15 slip elevators, the combination of a tubing elevator having a pair of pipe encircling members with hinge means connecting the same to enable the said members to swing apart to open the elevator, one of said pipe encircling members having a pair of oppositely disposed outwardly projecting lugs; 20 a supporting link for each lug having an eye receiving its corresponding lug, at least one of said lugs having a balance bolt mounted therein with a head located in the space between the lug and the adjacent face of the eye, and a cap removably 25 attached to the head of the bolt for engaging the face of the eye adjacent the bolt head to hold the elevator substantially upright when open.

2. In a balance stop construction for door type 30 slip elevators, the combination of a tubing elevator having a pair of pipe encircling members with hinge means connecting the same to enable the said members to swing apart to open the elevator, one of said pipe encircling members having a pair of oppositely disposed outwardly projecting lugs, a supporting link for each lug having an eye receiving its corresponding lug, at least one of said lugs having a balance bolt mounted therein with a head located in the space between the lug and the adjacent face of the eye, and a cap having 35 a slot to slide laterally over the bolt head, the outer face of said cap operating to engage the face of the eye adjacent the bolt head to hold the elevator substantially upright when open.

3. In a balance stop construction for door type 45 slip elevators, the combination of a tubing elevator having a pair of pipe encircling members with hinge means connecting the same to enable the said members to swing apart to open the elevator, one of said pipe encircling members having a pair 50 of oppositely disposed outwardly projecting lugs, a supporting link for each lug having an eye receiving its corresponding lug, at least one of said lugs having a balance bolt mounted therein with a head located in the space between the lug and the adjacent face of the eye, a cap having a slot to slide laterally over the bolt head, the outer face of 55 said cap operating to engage the face of the eye adjacent the bolt head to hold the elevator substantially upright when open, and means for securing the cap on the bolt.

4. In a balance stop construction for door type 60 slip elevators, the combination of a tubing elevator having a pair of pipe encircling members with hinge means connecting the same to enable 65 the said members to swing apart to open the elevator, one of said pipe encircling members having a pair of oppositely disposed outwardly projecting lugs, a supporting link for each lug having an eye receiving its corresponding lug, at least one of said lugs having a balance bolt mounted therein with a head located in the space between the lug and the adjacent face of the eye, and a cap removably attached to the head of the bolt 70 for engaging the face of the eye adjacent the bolt 75

head to hold the elevator substantially upright when open, said lug having means for engaging the side of said cap to hold the same and the bolt against rotation.

- 5. In a balance stop construction for door type slip elevators, the combination of a tubular elevator having a pair of pipe encircling members with hinge means connecting the same to enable the said members to swing apart to open the elevator, one of said pipe encircling members having a pair of oppositely disposed outwardly projecting lugs, a supporting link for each lug having an eye receiving its corresponding lug, at least one of said lugs having a balance bolt mounted therein with an angular head located in the space between the lug and the adjacent face of the eye, and a cap removably attached to the head of the bolt for engaging the face of the eye adjacent the bolt head to hold the elevator substantially upright when open, the side faces of said bolt head having threaded sockets therein, and the butt of said cap having a pin therein to be received in one of the sockets to retain the cap on the bolt head.
- 6. In a balance stop construction for door type slip elevators, the combination of a tubing elevator having a pair of pipe encircling members with hinge means connecting the same to enable the said members to swing apart to open the elevator, one of said pipe encircling members having a pair of oppositely disposed outwardly projecting lugs, a supporting link for each lug having an eye receiving its corresponding lug, at least one of said lugs having a balance bolt mounted therein with a substantially square head located in the space between the lug and the adjacent face of the eye, a cap removably attached to the head of

the bolt and constructed to slide onto the same from the side, for engaging the face of the eye adjacent the bolt, the butt end of said cap having a threaded pin swiveled therein with the threads of the pin located at its inner end, the side face of said head having a threaded opening to receive the threaded end of the pin.

- 7. In a balance stop construction for door type slip elevators, the combination of a tubing elevator having a pair of pipe encircling members with hinge means connecting the same to enable the said members to swing apart to open the elevator, one of said pipe encircling members having a pair of oppositely disposed outwardly projecting lugs, a supporting link for each lug having an eye receiving its corresponding lug, balance bolt means mounted in at least one of said lugs, a cap carried by the said last-named means for engaging the adjacent face of the eye, and co-operating with the same to enable an adjustment of said cap into substantial contact with the adjacent face of said eye to hold the elevator substantially upright when open.

8. An elevator having a pair of pipe encircling members with hinge means connecting the same to enable the said members to swing apart to open the elevator, one of said pipe encircling members having a pair of oppositely disposed outwardly projecting lugs, in combination with a balance bolt mounted in one of said lugs, and a cap mounted on the outer end of said bolt to co-operate with the eye of a supporting link to maintain the elevator in an upright position when the same is open.
